AMALGAMATOR

Winfield S. De Lisle, Colonia, N. J.

Application November 27, 1935, Serial No. 51,958

9 Claims. (Cl. 209—205)

The present invention relates to amalgamators for extracting gold and other precious metals from ore in a pulverized or finely divided state.

One of the primary objects of the invention is to provide an amalgamator which is capable of extracting a greater portion of the gold or metal from the ore than has heretofore been possible, thus rendering it profitable to extract gold or other metal from ore in which the gold or metal is present in relatively small proportion and which it has heretofore been unprofitable to extract.

A more particular object of the invention is to provide an amalgamator wherein the ore containing the gold or other metal is forced downwardly into a bath of mercury in a manner which will effectively expose the gold or metal to the mercury, thus insuring amalgamation of such gold or metal as the ore may contain, with the mercury.

Another object is to provide an amalgamator wherein feed water and the ore are carried down into the mercury and spread so that any gold or metal contained in the ore will be amalgamated by the mercury and flaky or other particles of the gold or metal which tend to float will be prevented from washing away with the tailings and thus lost.

Another object is to provide novel means for submerging the ore in the mercury whereby effective contact between the ore and mercury is produced without undue agitation of the mercury, thus minimizing flouring of the mercury.

A further object of the invention is to provide in an amalgamator means for supplying wash water to remove the tailings from the mercury, in combination with a baffle over which the tailings pass and which protects the mercury which lies beneath it.

To these and other ends, the invention consists in certain improvements and combinations and arrangements of parts all as will be herein-after more fully described, the features of novelty being pointed out more particularly in the claims at the end of this specification.

In the accompanying drawings:—

Figure 1 is a top plan view, partly in section, of an amalgamator constructed in accordance with the present invention;

Figure 2 is a vertical longitudinal section of the amalgamator shown in Fig. 1;

Figure 3 is a transverse vertical section, on an enlarged scale with portions broken away;

Figure 4 is a vertical section taken on the line 4—4 in Fig. 3; and

Figure 5 is a detail view of one of the distributor pipes for supplying feed water or wash water.

Similar parts are designated by the same reference characters in the several figures.

The amalgamator shown in the present instance is particularly adapted for the extraction of fine particles of gold from ore in a pulverized state or state of fine subdivision, but it is to be understood that the invention is applicable to the extraction of other metals capable of amalgamating with mercury and that the invention is not restricted to the precise construction shown since equivalent constructions are contemplated and such will be included within the scope of the claims.

The amalgamator, as shown in the present instance, comprises a suitable frame which may consist of longitudinally extending laterally spaced side members 1 and a connecting cross member 2, this frame supporting within it a pan 3 or receptacle 3, composed preferably of sheet iron or other suitable metal which will not amalgamate with mercury, this pan being supported within the frame by a suitable number of angle irons 4. This pan or receptacle forms a well in which is contained a body or bath of mercury 5, and the bottom of the well is provided with an opening 6 through which the amalgamated gold may be withdrawn from time to time, this opening being normally closed by suitable means such as by a screw plug 7. The portion 8 of the pan toward the end thereof which receives the ore is at a level slightly higher than the portion 9 thereof at which the ore tailings are discharged, the portion 9 preferably sloping downwardly to a tailings discharge chute 10. The pan is filled with the mercury to a level x which is slightly below the edge 9^a over which the tailings discharge in order to prevent discharge of the mercury from the pan, but permit the tailings to discharge from the surface of the body of mercury.

A drum 11 is mounted on the frame in cooperative relation with the mercury containing pan or receptacle. As shown in the present instance, this drum comprises a cylindrical peripheral portion 12, which may be composed of wood or other suitable material not affected by the mercury, and a pair of circular end members or heads 13 which may be composed of iron or other suitable material inert to the mercury, the heads of the drum being clamped against the ends of the cylindrical portion 12 thereof by a suitable number of tie bolts 14. The drum is supported rotatably in the frame by a shaft 15 which is

fixed in the heads 13 and is journaled to rotate in bearings 16 which may be supported on the side members 1 of the frame, and this shaft is provided with suitable means for rotating it, as 5 for example a belt pulley 17 fixed on this shaft.

The cylindrical or peripheral portion 12 of the drum has a series of flights or blades 18 arranged thereon in circumferentially spaced relation around its circumference and extending between the heads 13 of the drum. These flights extend longitudinally of the drum but are arranged preferably at a slight angle to the axis of the drum so that the ends of the flights at one end of the drum will be slightly in advance of the 10 ends thereof at the opposite end of the drum, for a purpose which will hereinafter appear. The flights 18 are preferably of angle form in cross section, one flange of each flight being secured to the periphery of the portion 12 of the drum 15 and the other flange thereof projecting outwardly from the periphery of the portion 12. The flights are preferably somewhat longer than the peripheral portion 12 of the drum, and the inner faces of the heads 13 are preferably provided 20 with coatings 19 of rubber which may be vulcanized in recesses 20 in the inner faces of the heads 13, so that when these heads are drawn together by the tie bolts 14, the ends of the flights will become imbedded more or less in 25 these rubber surfaces, thereby providing fluid-tight joints between the heads 13 and the ends of the flights, and the ends of the peripheral portion 12 of the drum will form fluid tight joints with the heads 13.

The drum is mounted at such a height in relation to the pan 3 that the under side of its cylindrical peripheral portion 12 will be approximately tangential to the surface x of the body of mercury 5 but will dip slightly below said 30 surface, and the flights projecting outwardly from the surface of the peripheral portion 12 will be immersed in the mercury and will travel therethrough during rotation of the drum. The flights are composed preferably of so-called galvanized iron, that is iron coated with zinc, it having been found that the presence of zinc in the mercury bath promotes or facilitates the amalgamation of the gold with the mercury. In order to prevent the passage of water or ore 35 around the ends of the drum, sealing strips 20, composed of rubber or other suitable material are secured to the inner sides of the frame members 1, these sealing strips extending downwardly to the lower edges of the heads 13 and having 40 a wiping contact with the outer sides of these heads of the drum, thereby completely sealing the spaces at the ends of the drum and making it impossible for anything to pass to the discharge side of the drum without passing down through 45 the mercury.

A hopper 21 is mounted on the frame at one side of the drum and above the portion 8 of the pan, this hopper being adapted to receive the gold-containing ore in a pulverized or finely divided state, the lower portion of this hopper having an inclined bottom 22 and a discharge opening 23 which may be controlled by a vertically adjustable gate 24 which regulates the rate of feed of the ore to the amalgamator. The inclined bottom 22 of this hopper is preferably extended downwardly between the heads 13 of the drum and to a level slightly above the surface of the body of mercury in the pan, so that the ore will be fed at a point close to the surface 50 of the body of mercury and in close relation to

the periphery of the drum. Feed water is fed to the amalgamator with the crushed ore or through a pipe 25 which is connected to a horizontal distributing pipe 26, the latter being located preferably beneath the inclined bottom 22 of the ore supply hopper 21 and having a series of perforations 27 therein disposed at such an angle as to discharge feed water beneath the lower edge of the inclined hopper bottom 22 and against the ore as the latter comes into contact with the body of mercury. A wash water pipe 28 is provided, it supplying wash water to a distributing pipe 29 located at the opposite side of the drum, the distributing pipe having a series of perforations 30 therein disposed to project jets 15 of wash water against the periphery of the drum, thereby washing any small globules of mercury, or particles of ore or gold which might adhere to the drum and tend to be lifted thereby from the body of mercury. A baffle or plate 31 is also 20 preferably provided, it being supported to extend across the mercury containing pan substantially at the level of the surface x of the body of mercury, this baffle or plate being inclined downwardly toward the tailings discharge end of 25 the pan, and the wash water distributing pipe 29 is provided with a series of openings 32 arranged to project wash water onto the upper surface of the inclined baffle or plate 31.

In order to prevent loss of any mercury which 30 may have become floured or broken into small particles during the operation of the amalgamator, a pair of electrodes 34 and 35 are provided at or adjacent to the ends of the mercury containing pan 3, these electrodes being submerged in the mercury immediately below the surface thereof, these electrodes being supported in the pan by suitable insulators 36 and being connected to a suitable source of electric current 37 which supplies electric current to the 40 electrodes during the operation of the amalgamator.

In operation, the pan or receptacle 3 is supplied with a body of mercury 5 to a level x which is slightly below the edge or lip 9^a over which the tailings discharge, the drum is revolved continuously and at a relatively low speed, as for example about ten revolutions per minute, the ore containing the gold, and which may be crushed or otherwise finely divided is supplied to the feed hopper 21, and feed water and wash water supplied to the pipes 25 and 28 respectively. The crushed or finely divided ore is fed by the hopper 21 to the surface x of the body of mercury in the path of the flights 18 on the drum, which revolves in an anti-clockwise direction in Figure 2. As the flights enter the body of mercury they trap beneath them the ore fed from the hopper 21 and which is flowed toward the drum by the jets of water from the distributing pipe 26, and the ore thus trapped beneath the flights, together with water and sand or other material associated with the ore is forced down into the body of mercury and is discharged at the opposite side of the drum. During the carrying of the ore through the body of mercury by the flights on the drum, the ore is spread, by the upward pressure of the mercury, against the periphery of the cylindrical portion 12 of the drum, thus spreading the ore into a thin layer which insures contact of the mercury with any free gold contained in the ore so that such gold will be effectively amalgamated by the mercury, and the amalgamated gold, being heavier than the mercury, will sink to the bottom of the mercury con- 75

taining pan. The tailings or sand carried beneath the drum by the rotation thereof and which floats on the surface of the body of mercury, will be washed over the discharge edge or 5 lip 9^a and will discharge over the chute 10, the discharge of the tailings being assisted by the wash water from the distributor pipe 29. The wash water from the openings 30 in this distributor pipe and which are projected against the 10 periphery of the drum and the flights thereon, will effectively wash any particles of mercury, gold or other material which might adhere to the drum and be lifted from the mercury, and the jets of wash water from the openings 32 in 15 the distributor pipe 29, which discharge at an angle toward the tailings discharge lip 9^a, will act to advance the tailings toward the tailings discharge. By arranging the jets of wash water from the openings 32 to discharge on the 20 upper side of the downwardly inclined baffle or plate 31, the tailings will be discharged over this plate toward the tailings discharge, the baffle 31 preventing undue agitation of the mercury by these wash water jets. By arranging the 25 flights 18 on the periphery of the drum at an angle to the axis thereof so that the ends of the flight at one end of the drum are somewhat in advance of those at the other end of the drum, the flights will enter the bath or pool of mercury 30 progressively, from one end to the other, thereby avoiding impact between the flights and mercury which would tend to flour it, and since the substantially radial portions of the flights are nearly vertical when they enter the mercury, 35 since the periphery of the drum is immersed to only a small depth in the mercury, impact of the flights on the mercury is thus further reduced, thereby further minimizing flouring of the mercury. The gold which is amalgamated by the 40 mercury during the passage of the gold containing ore therethrough, settles to the lowermost portion of the mercury containing pan 3, and the amalgamated gold may be removed from the pan from time to time, by removing the plug 1. 45 The gold may be separated from the amalgam in any suitable and well-known way, as by vaporization of the mercury.

By immersing the revoluble drum only slightly below the surface of the bath or pool of mercury, the pulp or gold bearing ore is all carried beneath the surface of the mercury so that no portion of the ore can discharge until after it has been exposed to the mercury, thus affording an opportunity for the mercury to amalgamate with any gold contained in the ore. Since the feed water must also pass through the mercury before discharging, there is no opportunity for flaky or light gold, or flour or float gold that is held in suspension in the water due to 50 surface tension, to float or be washed away to the outlet and thus lost, but such gold will be submerged in the mercury and amalgamated therewith.

The shallow immersion of the lower side of 55 the periphery of the drum causes the projecting flights on the drum to contact with the mercury first at their outer edges, thereby trapping or pocketing the ore beneath the flights so that it cannot escape and therefore must enter the mercury as the drum revolves and such manner of contact of the flights with the surface of the mercury takes place substantially without impact or agitation of the mercury to the extent to cause flouring thereof, flouring of the mercury 60 being further minimized by the progressive en-

gagement of the flights, from end to end, with the surface of the mercury, due to the angular pitch of the flights with respect to the axis of the drum.

By feeding water to the ore as it is fed to the 5 surface of the mercury pool, the ore is spread and carried into position beneath the flights, and rotation of the drum causes the ore beneath the flights to be spread out, thus affording an opportunity for the mercury to contact with and amalgamate all particles of gold contained in the ore, before the ore reaches the tailings discharge, and all of the ore must pass through the mercury before reaching the tailings discharge, the drum and the sealing strips at the ends thereof 10 forming, in effect, a barrier between the ore feed hopper and the tailings discharge. 15

Since the flights extend only slightly below the surface of the mercury, they will not carry sand from the ore down into the lower portion of the 20 pool of mercury where it would mix with the amalgamated gold, which would be objectionable.

By providing the electrodes in the mercury and water pool, obstruction to the discharge of the 25 tailings over the surface of the mercury is avoided, and the electric current supplied to these electrodes will prevent loss of any mercury that may have become floured or broken into small particles, by causing such particles of mercury to become reunited with the pool. 30

I claim as my invention:—

1. An amalgamator comprising a receptacle containing a body of mercury, a drum having flanges at its ends and longitudinal flights on its periphery extending continuously between the flanges and at an incline to the axis of the drum, the drum being mounted rotatably with the lower side of its periphery in contact with the surface of the mercury, and means for feeding ore to the surface of the mercury at one side of the 40 drum. 35

2. An amalgamator comprising a receptacle containing a bath of mercury, a cylindrical drum having peripheral flanges and blade-like flights projecting radially from its periphery and extending continuously between the flanges at a slight angle to the axis of the drum, the drum being mounted to rotate with the lower side of its periphery in contact with the surface of the mercury and to carry the flights thereon progressively from end to end into the mercury, and means for feeding ore to the surface of the mercury at one side of the drum. 50

3. An amalgamator comprising a receptacle containing a body of mercury, a drum having flights projecting from its periphery and mounted to rotate with the lower side of its periphery in contact with the surface of the mercury, means for feeding ore and jets of water to the same area of the surface of the mercury at one side of the drum, a baffle plate mounted at the other side of the drum and having an upper surface disposed substantially at the level of the surface of the mercury and inclined downwardly away from the drum, and means for injecting 65 wash water against the other side of the drum to wash ore therefrom for discharge over the baffle. 60

4. An amalgamator comprising a receptacle containing a body of mercury, a drum having flights projecting from its periphery and mounted to rotate with the lower side of its periphery in contact with the surface of the mercury, means for feeding ore and water to the same area of the surface of the mercury at one side of the drum, 70

a baffle plate having an upper surface disposed substantially at the surface of the mercury at the other side of the drum and inclined away from the drum for the passage thereover of ore discharged from the drum, and means for injecting water onto the upper surface of said baffle plate to wash tailings thereover.

5. An amalgamator comprising a receptacle containing a bath of mercury, means for feeding 10 ore and water to the surface of the mercury, a drum mounted to rotate with its periphery located approximately tangentially to the surface of the mercury, the drum having circumferential flanges at its ends and flights projecting 15 from its periphery and extending continuously between said end flanges at an incline to the axis of the drum, the flights being submergeable progressively from end to end in the bath of mercury and movable through the mercury during 20 relatively low speed of rotation of the drum to submerge the ore and water below the surface of the mercury and thereby amalgamate flour gold in suspension in the water, and means for projecting wash water against the flights on the 25 drum as the flights emerge from the bath of mercury.

6. An amalgamator comprising a pan containing a bath of mercury and having a discharge at one end located approximately on the level of the 30 surface of the mercury, a drum mounted rotatably with the lower side of its periphery approximately tangential to and in contact with the surface of the mercury, means for feeding ore and water to the surface of the mercury at 35 one side of the drum, a baffle plate mounted at the discharge side of the drum and having an upper surface substantially at the level of the surface of the mercury to receive ore discharged from the drum, said upper surface of the baffle 40 plate being inclined downwardly toward the discharge, and means for projecting jets of wash water against the upper side of the baffle plate and toward the discharge.

7. An amalgamator comprising a pan containing a bath of mercury and water and having a

discharge at one end located approximately on the level of the surface of the mercury, a drum mounted rotatably with the lower side of its periphery approximately tangential to and in contact with the surface of the mercury and having flights projecting from its periphery and extending at an incline to the axis of the drum, means for feeding ore and water to the surface of the mercury at one side of the drum, a baffle plate located at the other side of the drum and having an upper surface located substantially at the level of the surface of the mercury and inclined downwardly toward said discharge, and means for projecting water onto said upper surface of said baffle plate and also against the 15 adjacent side of the drum.

8. An amalgamator comprising a receptacle containing a body of mercury, and a drum mounted with the lower side of its periphery in contact with the surface of the mercury and comprising a pair of end heads having surfaces of yielding material applied to their inner sides adjacent to their peripheries, and an annular series of circumferentially spaced flights extending longitudinally of the drum between said heads 25 and having their ends clamped and sealed against said surfaces of yielding material.

9. An amalgamator comprising a receptacle containing a body of mercury, and a drum mounted with the lower side of its periphery in 30 contact with the surface of the mercury and comprising a pair of end heads provided at their inner sides and adjacent to their peripheries with coatings of rubber, a cylindrical peripheral portion extending between said heads and engaging 35 at its ends with said rubber coatings on said heads, an annular series of flights arranged in circumferentially spaced relation around the periphery of said cylindrical portion and engaging at their ends with said rubber coatings on 40 said heads, and means for drawing said heads together to embed and seal the ends of said cylindrical portion and the flights in said rubber coatings.

WINFIELD S. DE LISLE. 45
